SIDNEY WOOLF AND CHARLES W. RAFFERTY, OF LYNCH, NEBRASKA.

CONDENSING SYSTEM.

932,226.

Specification of Letters Patent. Patented Aug. 24, 1909.

Application filed December 14, 1908. Serial No. 467,495.

To all whom it may concern:

Be it known that we, SIDNEY WOOLF and CHARLES W. RAFFERTY, citizens of the United States, and residents of Lynch, in the county of Boyd and State of Nebraska, have made certain new and useful Improvements in Condensing Systems, of which the following is a specification.

Our invention relates to improvements in jet condensers, and consists in the constructions, combinations and arrangement of parts herein described and claimed.

An object of our invention is to provide a novel means for disposing of the exhaust steam by condensing the same thereby providing means for overcoming back pressure.

A further object of our invention is to provide means for removing the impurities which are carried along with the steam thereby leaving the feed water in a pure condition for immediate reentrance into the boiler.

Further objects and advantages will appear in the following specification, and the novel features of the invention will be particularly pointed out in the appended claims.

Our invention is illustrated in the accompanying drawings, in which,

Figure 1 is a view, partly in section, showing the arrangement of the condensing devices, and Fig. 2 is a section through the jet condenser, shown in Fig. 1.

Referring now to the drawings A denotes in general a steam engine which is supplied by means of the steam pipe B, and is provided with an exhaust pipe C, which leads to the condenser. The latter consists of a depending pipe D with which the cold water pipe E communicates, the latter having a downwardly turned end e, and being controlled by the valve v. The pipe D has a reduced portion d, within which is a spreader or spraying device F. This consists of a stem provided with a head f. The bottom part of the stem is turned at right angles and is arranged to enter an opening f' in the reduced portion d of the pipe D. The spreader F is held in this slot by means of two nuts f² on the outside and inside respectively, of the wall of the pipe d. This construction enables the spreader to be brought nearer or farther away from the open end e of the pipe E thereby restricting the opening and causing the water therefrom to enter the pipe D in a thin sheet or spray which mingles with the exhaust steam thereby causing the rapid condensation of the latter.

As the water and steam pass down the pipe d they impinge a second spreader or mixer G, which is located in a vessel H, the latter being either an enlargement of the pipe d or a separate vessel connected therewith in the usual manner. The mixer G consists of the convex disk g suspended at its center by means of the bent rod g', which is adapted to pass through the slot g² and to be held by the nut g³. The mixer G may be adjusted in the same manner as the spreader F from the exterior of the device.

It will be noted that the vessel H is heart-shaped in cross section. The cold water pouring on the top of the disk is brought into intimate contact with the steam which has to pass around the edge of the disk and is directed upwardly against it on its lower side.

From the vessel H the steam and water pass downwardly into the receiver or hot well J. This vessel consists preferably of a steel shell of air tight construction provided with the stuffing box j' at its top for the entrance of the pipe d. The hot well J communicates with the settling tank K. The latter is provided with a galvanized iron hood L, having a pipe l at its top and being provided with the screens s. This hood is arranged to fit over the tank K in the manner shown in the figure. The air pipes M communicate with the tank K above the level of the water, while the pipe O leads to the cistern P.

The foregoing description of the various parts of this system will be sufficient for an understanding of the operation thereof. The exhaust steam passing through the pipe C meets the stream of cold water coming in through the pipe E. The latter is spread out in a thin stream as already explained, and the hot steam is condensed partially and flows with the water down the pipe d. The condensation of the steam produces a vacuum which decreases the back pressure on the engine. On reaching the mixer G the steam is again brought into intimate contact with the water and further condensation takes place. The condensed steam and water flows into the hot well J, the end of the pipe d being preferably always below the level of the water in the well. When the water rises in the well above the pipe N, it overflows into the tank K. The end of the pipe N being underneath of the water in the tank J prevents the reduction of the vacuum created

by the condensation of the steam. It will be seen that the end of the pipe *d* goes considerably below the water level and the incoming steam causes an agitation of the water so that the impurities are carried out by the pipe *N* into the tank *K*, where they are allowed to settle. If any steam is carried over by the pipe *N* it is immediately condensed by coming in contact with the cold air entering the pipes *M*. In order to provide an additional means for condensing the steam I arrange the screens *s* in the hood *L*. These screens provide extended surfaces which rapidly extract the heat from the steam and cause a complete condensation of the latter. The pipe *L* is for the purpose of conveying away the heat which would otherwise be confined in the hood. The water in the tank *K* after having been relieved of its settling now overflows into the cistern *P* from whence it may be pumped immediately into the boiler through the pipe *R* in a pure state.

We claim—

- 25 1. In a condensing system, an exhaust pipe, a cold water pipe communicating therewith, means for spraying the incoming stream, a hot well, a pipe leading therefrom, a settling tank communicating with said well through said pipe, means in said settling tank for the further condensation of the steam, a cistern, and an outlet pipe leading from said settling tank to said cistern.
- 30 2. In a condensing system, an exhaust pipe, means for condensing the steam from said exhaust pipe, a hot well in communication with said condensing means, a settling

40 tank, a pipe connecting said hot well with said settling tank, one end of said connecting pipe being normally below the surface of the water in said hot well, and the other end being above the surface of the water in said settling tank, a cistern, and a pipe leading from said settling tank to said cistern.

45 3. In a condensing system, an exhaust pipe, means for condensing the steam from said exhaust pipe, a hot well in communication with said condensing means, a settling tank, a pipe connecting said hot well with 50 said settling tank, one end of said connecting pipe being normally below the surface of the water in said hot well, and the other end being above the surface of the water in said settling tank, means for the admission of 55 cold air into said settling tank, a hood for said settling tank provided with transverse screens and having an exit, a cistern, and a pipe leading from said settling tank to said cistern.

60 4. In a condensing system, an exhaust pipe, a cold water pipe communicating therewith, a spreader adjustably secured within said pipe and provided with a conical head arranged to cooperate with the end of 65 said cold water pipe for spraying the incoming stream, a receptacle located below said spreader, a mixing device suspended within said receptacle, and means for collecting the settling of the condensed water.
